Attorney

UNITED STATES PATENT OFFICE.

ALBERT H. BENWELL, OF ST. LOUIS, MISSOURI.

WRENCH.

1,351,276.

Specification of Letters Patent. Patented Aug. 31, 1920.

Application filed March 1, 1920. Serial No. 362,445.

To all whom it may concern:

Be it known that I, ALBERT H. BENWELL, a citizen of the United States, residing at St. Louis, State of Missouri, have invented 5 certain new and useful Improvements in Wrenches, of which the following is a specification.

This invention relates to certain new and useful improvements in wrenches, the peculiarities of which will be hereinafter described and claimed.

The main object of my invention is to provide a two-piece wrench of durable, efficient, and quickly adjustable design; and 15 secondly to provide one that is capable of reversing one jaw to secure wide range of adjustment.

In the accompanying drawing on which like reference letters indicate corresponding parts, Figure 1 represents a face view of 20 a wrench embodying my improvement; Fig. 2 a side edge view of the same, Fig. 3 a detail side edge view of my auxiliary jaw; Fig. 4 a detailed face view of said jaw; and 25 Fig. 5 a face view of the lower end of the main jaw as in Fig. 1, with the auxiliary jaw reversed therein.

The letter A designates the main jaw of a wrench exemplifying my improvements 30 having a head B formed by cheek plates on opposite side of a slot C between said plates. Said slot is traversed by a pin D located substantially in the center of said head as shown in Fig. 1 and riveted or otherwise 35 securely fastened in the head so as to be practically integral therewith. This pin may extend wholly across the slot C or only partially so such as a projection, but it is stronger construction for the pin to engage both cheeks of the head B. Extending 40 outward from the head opposite to the jaw A, is a handle E of any suitable length. The jaw A is curved laterally with regard to the axis of the head and handle as shown in Fig. 1. This constitutes the main member 45 of the wrench.

The other member consists of an auxiliary head composed of a jaw F serrated as shown, and provided with a reduced or thinner 50 shank G, extending outward more or less at a right angle to the curved jaw F, and having in said shank a series of notches H, H¹ and H², of such size that they will readily engage selectively with the pin D in the slotted head. Three notches are shown 55

in this design of the auxiliary head and it will be seen from the detail view Fig. 4, that the notches are curved toward the head F so as to form hooks and thereby more readily retain their selective mounted position respectively upon said pin D. The location of the ends of the curved slots in said shanks is such that the gripping action of the jaw F upon the pipe or other article engaged between the jaws A and F, will 60 be increased by a movement of the handle E in the direction F of the arrow Fig. 1, by which the jaw F will pull into closer engagement with the article gripped. Any number of slots may be provided. At the 65 opposite end of the shank G from the jaw F, is a hole I that is adapted to receive a spring pin J Fig. 2, which will maintain its position in the hole I ordinarily, but may be readily pulled out when desired. 70 The pin is like a split cotter pin having its two halves bowed outward near the end opposite the head, forming a swelled portion a little larger than the hole I, and leaving the pin of normal size between the swell 75 and the head. The pin J prevents accidental disengagement of the shank from the slot in the head B, on account of the head and end projecting from the sides of the shank, and yet allows the ready adjustment 80 of any slot and consequent varied location of the jaw F when the pin selectively engages the respective slots.

It will be observed that when the auxiliary jaw is inserted from one side of the 85 slotted head as shown in Fig. 1, the jaws A and F oppose each other being curved concave in opposite directions, and by adjustment of the auxiliary jaw comparatively large pipe or other objects such as nuts, may 90 be gripped between said jaws. The opposing faces of the jaws A and F are serrated in opposite directions regarding the inclination of the teeth, so that the pulling action on the auxiliary jaw will be opposed by the 95 pushing action on the teeth of the main jaw A. When it is desired to engage comparatively small articles either of pipe or plate form, the detachable pin J is pulled out from its hole in the end of the shank G and 100 the shank is inserted from the other side of the slotted head and engaged with the pin as shown in Fig. 5. In this latter position the curved jaws A and F are more nearly 105 parallel, as distinguished from their oppo- 110

sitely curved position in Fig. 1, and thereby are adapted to grip curved plates or flat plates or other thin plate articles between the generally parallel surfaces. The outer side edge of the jaw A is preferably serrated by teeth that incline opposite to those in the jaw F when mounted as in Fig. 5, for better engagement with the article to be gripped.

10 Thus it is evident that by means of this slotted shank of the auxiliary jaw the relative position of the jaws A and F may be quickly changed; also that by reversing the auxiliary jaw in the slotted head, a finer gripping engagement may be effected by the more nearly parallel arrangement of the curved jaws in the latter position. Thus a wide range of adjustment is readily effected and the change from one adjustment 15 to another is made without screw threaded engagement which is liable to wear and subject to damage. In my construction simplicity is attained as the wrench is practically in two members only and the wearing parts are provided with large bearing 20 surfaces.

I claim:

1. A wrench comprising a main jaw ser-

rated on both sides and having a slotted head and a handle, and having a pin traversing the slot in said head, an auxiliary jaw having a shank with notches therein curved to form hooks adapted to engage selectively the pin in said head, and adapted to enter said slotted head from either side 35 and engage said pin and thus adjustably cooperate with both sides of said main jaw.

2. A wrench comprising a slotted head provided with a pin across the slot, and having a handle and a jaw curved laterally 40 with regard to said head and serrated on both sides, and an auxiliary jaw and shank curved laterally with regard to each other and provided with notches on said shank adapted to engage selectively with said pin,—said shank being insertible into the slotted head from either side and the auxiliary jaw being thereby generally parallel to the main jaw for gripping plate or small pipe, or curved opposite to the same when 45 reversed for gripping relatively larger pipe, and variably adjustable in both positions substantially as described.

In testimony whereof I have affixed my signature.

ALBERT H. BENWELL.
